UNITED STATES PATENT OFFICE.

HENRY KEISER, OF BLOOMINGTON, ILLINOIS.

DUST-COLLECTOR.

SPECIFICATION forming part of Letters Patent No. 308,898, dated December 9, 1884.

Application filed April 15, 1884. (No model.)

To all whom it may concern:

Be it known that I, HENRY KEISER, of Bloomington, in the county of McLean, and in the State of Illinois, have invented certain new and useful Improvements in Dust-Collectors; and I do hereby declare that the following is a full, clear, and exact description thereof, reference being had to the accompanying drawings, and to the letters of reference marked thereon, making a part of this specification.

This invention relates to that class of milling machinery known as "dust-collectors;" and it has for its object to provide simple mechanism for automatically supplying and cutting off an air-blast to the dust-chambers, for the purpose hereinafter described; and this result I accomplish by the means and in the manner hereinafter fully described and claimed, due reference being had to the accompanying drawings, forming part of this specification, wherein—

Figure 1 is a broken sectional elevation of two dust-chambers placed one above the other; Fig. 2, a horizontal plane taken on the line xx of Fig. 1, and Fig. 3 an enlarged view of the valve for deflecting the air-blast from one chamber to the other and the means for operating the same; Fig. 4, a detailed sectional view of one of the knocker-arms and one of the inclined blocks or cams it engages with in its revolutions.

In flour-mills dust and fine flour are constantly being thrown off from the bolts and millstones into the atmosphere, which not only renders the air unhealthy, but also deposits the dust upon the journals and running parts of the machinery, tending to choke the same; and the accumulation of dust in time increases the danger of fire, which is always more or less imminent in mills of this and other classes. Various dust-collectors have been devised to obviate this disadvantage, with more or less success, and the present invention is designed to effectually accomplish this result in the manner and by the means hereinafter described.

Referring to the drawings, the letters A A' indicate two dust-chambers placed one above the other. These dust-chambers are preferably 50 constructed of circular form in cross-section,

and are provided with a series of frames, over which are stretched cloths in such manner that as the air is forced through them the dust will be arrested and held by the cloths. These frames are of such well-known construction 55 that no special description of the same will be needed. The lower dust-chamber, A, is provided with a central air-passage, B, extending vertically through the center of the same and communicating at its lower end with the cloth-frames of said dust-chamber A, and at its upper end with the dust-chamber A'.

C indicates the air-trunk for conveying the dust-laden air from the bolts or millstones, the air being forced through the same by a fan, 65 or by any of the well-known means employed for the purpose in this class of machinery, said air-trunk being connected with and discharging into the central air-passage, B, as shown.

D indicates a shaft extending up vertically through the center of both the dust-chambers A and A', said shaft being rotated by connecting the same by suitable gearing with any portion of the milling machinery.

E indicates scraper-arms, rigidly mounted upon said shaft D, and revolving with a scraping action upon the bottoms of the dust-chambers A A', sweeping the accumulated dust out through openings e, whence it is conveyed by 75 70 a suitable hopper or troughs to bins or other receptacles designed to receive the dust.

F indicates knocker-arms mounted upon said scraper-arms E, and provided upon their extremities with rollers f, which come in contact with inclined blocks or cams e' e', as shown in Fig. 1, secured to the under sides of the cloth-frames, and thus impart at each revolution of the shaft D a violent agitation to said frames, shaking the dust from the cloths that 85 90 has accumulated thereon. In the present instance I have only shown two inclined blocks or cams to each collecting-chamber; but it is evident they may be increased to any desired number that may be found expedient, in order 95 to give the necessary agitation to the cloth-frames by the spring-knockers.

In order to effectually dislodge the dust from the dust-cloths it is necessary that the air be alternately shut off from the dust-chambers, 100

for the reason that if the cloth-frames in both chambers were all the time to be subjected to the blast the force of the blast would hold the particles of dust against the cloth, and in order 5 to exclude the blast from one dust-chamber and allow the other chamber to continue separating the air from the dust I provide an automatic device constructed and arranged as follows:

- 10 Within the central air-passage, B, and at the discharge end of the air-trunk C, I place a cut-off valve, G. Said valve is rigidly secured to and moves with a rock-shaft, g, mounted in suitable bearings. Affixed to one 15 extremity of said shaft g is a crank, h, pivoted to a pitman, i, the other end of said pitman being supported in a horizontal position by a pivoted arm, i', as shown, or by bearings of any suitable nature. The pitman i is provided 20 with beveled recesses j j'.

k indicates a gear-wheel mounted in suitable bearings and provided with a roller wrist-pin, k', said gear-wheel being so arranged with respect to the pitman i that the wrist-pin k' 25 will alternately engage with the beveled slots j j' in its rotation. Said gear-wheel k gears with a small gear-wheel, l, which is mounted on a shaft carrying a beveled gear-wheel, m, several times larger than the gear-wheel l, and 30 the said beveled wheel m gears with a beveled wheel, n, mounted on the central shaft, D.

The cut-off valve is operated as follows: The central shaft, D, being rotated as before described, communicates motion to the wheel, 35 k through the medium of the gearing above described, said wheel revolving at a very slow rate of speed, and as the wrist-pin k' enters and passes through the beveled slot j' the pitman will be forced to the right, drawing with 40 it the crank h and depressing the valve, so as to cut off the air-blast from the lower dust-chamber and direct it to the upper chamber. The rock-shaft g is provided at one extremity with a weighted arm, g', (the weight not being 45 shown,) to balance said shaft and the valve mounted thereon, so as to enable said valve to be turned with a small amount of power, and to maintain said valve in any position to which it may be turned. The knocker-arms 50 F in their rotation strike the cams on the lower portions of the cloth-frames and dislodge the dust, and the air-blast being shut off from the lower chamber the dust descends by gravity to the lower part of the chamber, 55 where it is swept off by the rotating sweepers E into the openings e, and is thence conveyed to the dust-receptacles.

When the wrist-pin reaches the beveled slot j, the pitman will be forced to the left, thus 60 raising the cut-off valve, shutting off the air-blast from the dust-chamber A', and discharging said blast to the lower chamber, A. The blast is thus automatically deflected from one to the other of the dust-chambers at regular 65 intervals.

From the foregoing description it will be

seen that the cloth-frames in both chambers are being continuously agitated, while the blast is alternately supplied and shut off from the same, for as long as the blast is on the 70 frames will intercept and hold the dust, whether said frames are being agitated or at rest; but as soon as the blast is shut off from one of the chambers the dust therein will fall from the agitated frames and be swept off, as 75 before described. It will thus be seen that one chamber is always collecting the dust while the other chamber is depositing the same from its cloths, there being no stoppage 80 of the dust-collecting machinery.

It will be understood that the above-described dust-collecting machinery is applicable to mills of every nature where dust is thrown off into the atmosphere by the machinery.

It will be readily observed by those skilled in the art to which my invention is especially designed that by my arrangement of one chamber above another, with a central air-passage common to both, as shown and described, I 90 am enabled to operate the mechanism for vibrating the cloth-frames in said chambers, as well as the mechanism for operating the valve that alternately shuts off the air-blast to said chambers, from a single vertical shaft passing 95 up through the central air-passage, thereby greatly simplifying the operating machinery, and also making the machine much more effectual in operation and adaptable to flour and other mills than in that class of machines 100 where the air-chambers are arranged side by side and have mechanism for operating a valve or valves to alternately shut off the air-blast to said chambers and mechanism for keeping the dust-cloth or other frames clear. 105

Having thus described my invention, what I claim is—

1. In a dust-collector, the combination of two dust-collecting chambers arranged one above the other, as shown, and having a central air-passage common to both, an air-trunk discharging into said central air-passage, a vertical rotating shaft, a valve, and means for automatically operating the same to deflect the air-blast from one chamber and convey it 110 to the other chamber, substantially as described.

2. The combination of two dust-collecting chambers arranged one above the other, and provided with cloth-frames, and having a central air-passage common to both, an air-trunk discharging into said central air-passage, a vertical rotating shaft, a valve, means for automatically operating the same to alternately deflect the air-blast from one chamber and 120 convey the same to the other chamber, and means for agitating the dust-cloths, substantially as shown and described.

3. In a dust-collector, the combination of two dust-chambers arranged one above the other, as shown, vertical cloth-frames arranged therein, a central air-passage common to both,

and a vertical rotating shaft having knockers arranged to engage said frames to jar the accumulated dust from the cloths, substantially as described.

- 5 4. In a dust-collector, the combination of two dust-collecting chambers, a central air-passage common to both, an air-trunk discharging into said central air-passage, a valve, and means for automatically operating the
10 same to deflect the air-blast from one chamber and convey it to the other, consisting of

the rock-shaft, to which said valve is secured, crank, recessed pitman, gear-wheel having wrist-pin, and means for operating said gear-wheel, substantially as shown and described. 15

In testimony that I claim the foregoing I have hereunto set my hand this 26th day of March, 1884.

HENRY KEISER.
